FIG IV

INVENTOR:

HARRY KISTER.

by Arthur E. Page,
Attorney.

UNITED STATES PATENT OFFICE.

HARRY KISTER, OF PHILADELPHIA, PENNSYLVANIA.

TOY WAGON.

Application filed October 11, 1924. Serial No. 742,992.

To all whom it may concern:

Be it known that I, HARRY KISTER, a citizen of the United States, residing at Philadelphia, in the county of Philadelphia and State of Pennsylvania, have invented a certain new and useful Improvement in Toy Wagons, whereof the following is a specification, reference being had to the accompanying drawings.

My invention relates to a toy wagon provided with means whereby it may be propelled by the occupant. My invention provides a wagon which is changeable to either of two forms in alternation, viz, first the ordinary "express" body form in which it may be used for the transportation of merchandise, by traction, in the ordinary manner, and, second, said body may be opened to afford access to a treadmill mechanism operatively connected with a rear wheel of the wagon; whereby the latter may be propelled by the weight of the occupant, which may be constantly shifted on the treadmill by walking or running movement of the occupant.

My invention includes the various novel features of construction and arrangement hereinafter more definitely specified.

In said drawings; Fig. I is a plan view of a wagon conveniently embodying my invention, with the body in the "express" form, adapted to be progressed by traction.

Fig. II is a plan view of said wagon with the body opened to afford access to the treadmill mechanism, and with the treadmill elements in cooperative position.

Fig. III is a side elevation of said wagon, in the form shown in Fig. I.

Fig. IV is a longitudinal sectional view of said wagon, taken on the line IV, IV in Fig. II.

Fig. V is a plan view of the idle roller of the treadmill mechanism, which as shown in Figs. III and IV, is arranged to support the weight of the operator.

In said figures; the wagon comprises the rectangular body 1, supported by the pair of rear wheels 2 and 3, and the pair of front wheels 4 and 5. Said wheel 2 is mounted to rotate freely upon the axle 6, which latter is journaled in the frame 7 rigidly connected with said body 1. However, said wheel 3 is rigidly connected with said axle 6 and is the driving wheel of the vehicle

arranged to be propelled by the treadmill mechanism hereinafter described.

Said front wheels 4 and 5 are respectively loosely mounted upon the non-rotatable axle 8, and the latter is rigidly connected with the frame 9 which is mounted to turn freely upon the king-bolt 10; the latter being in unitary relation with the brace bar 11 and rigidly connected with said body 1. Said frame 9 has at the top thereof the annular bearing 12 which is mounted to turn under the bearing 13 of said body 1, and thus uphold the latter. Said frame 9 is pivotally connected at 15 with the wagon tongue 16, which is the tractor element by which said wagon may be drawn when arranged in the lowered position shown in Figs I and III; in which position the seat 17, extending across the front of said body 1, may be occupied by a passenger. In that position of the device; the trap doors 19, which are connected by hinges 20 with the floor 21 of said body, are closed, as shown in Fig. I, and the hand rail 22, which is connected by the hinges 23 with said floor 21, is laid flat on the latter, as shown in Fig. I, so as to permit said body 1 to be used as a receptacle, or for any purpose for which an ordinary toy express wagon is adapted.

However, said hand rail 22 may be turned to the position shown in Figs. II and IV, against the braces 24 upon the respectively opposite side of said body 1, and be rigidly connected therewith by the hooks 26 which temporarily retain said hand rail 22 in such upright position, so that a child standing in said body 1 may be supported by grasping said hand rail. When said hand rail is thus raised; said doors 19 may also be raised and turned aside upon said floor 21, as indicated in Fig. II, to uncover the opening 28 which they normally close as shown in Fig. I. In such position; the operator may stand upon the endless belt 30 which is conveniently formed of heavy textile material provided with transverse slats 31, for engagement by the feet of the operator. The weight of the operator is supported by the idle roller 34 shown detached in Fig. V, which has the shaft 35 journaled in suitable bearings 36 which are rigidly connected with said body 1, upon opposite sides of the housing 37 surrounding said opening 28. Said endless belt 30 ex-

tends around the rollers 39 and 40, which are respectively provided with shafts 41 and 42 and journaled in bearings 43 and 44 which are rigidly connected upon opposite sides of

5 said housing 37. Said roller 39 has, intermediate of the width thereof and of said belt 30, the sprocket wheel 46 which is rigidly connected with said roller shaft 41, and engaged by the endless sprocket chain 47.

10 Said chain 47 extends around the sprocket wheel 48 which is rigidly connected with the shaft 42 of said roller 40 intermediate of the length of the latter and of the width of said belt 30. The purpose and effect of 15 the arrangement herein described is to properly connect said rollers 39 and 40 for simultaneous rotation without excessive tensile strain upon said endless belt 30; the major portion of such strain being borne by said 20 chain 47.

Said shafts 41 and 42 are respectively provided with ball bearings 50 and 51, and said belt 30 is so inclined that the weight of a child standing upon said belt causes 25 the latter to gravitate in the direction of the arrow, shown in Fig. IV, thus, incidentally, turning said shafts 41 and 42, and the latter is provided with the gear wheel 53 engaging the gear wheel 54, which is 30 rigidly connected with rear axle 6 so as to positively rotate said rear wheel 3 in the direction of the arrow, marked thereon in Fig. IV, when said belt is shifted in the direction of the arrow marked thereon, and 35 thus automatically progress the wagon forwardly, by the weight of the operator, which may, of course, be shifted forwardly momentarily by the operator walking or running in said opening 28 on said belt 30.

40 When the vehicle is arranged to be operated by the treadmill mechanism above described; said tongue 16 is upturned to the position shown in Fig. IV, in which it rests upon said hand rail 22 and may be used by 45 the operator to steer the vehicle by the dirigible wheels 4 and 5 while the operator stands upon said belt 30 and is supported by said hand rail 22.

Although the progress of the vehicle may 50 be checked by the operator remaining stationary upon said belt 30 until the latter, moving in the direction of the arrow, shown in Fig. IV, brings the heels of the operator against the rear portion of said housing 37; 55 however, I find it convenient to provide the wagon with the brake lever 56, which is pivoted at 57 upon the housing 37, and provided at its lower end with roller 58 arranged to bear upon the rubber tire 59 of 60 the rear wagon wheel 2.

I have found it convenient to embody my invention in a toy wagon of ordinary size and proportions as illustrated. However, it is to be understood that I do not desire 65 to limit myself to such embodiment, as va-

rious modifications may be made therein without departing from the essential features of my invention, as defined in the appended claims.

I claim:

1. In a toy wagon, the combination with a rectangular express body, having a pair of trap doors in the floor thereof, hinged on axes parallel with the length of said body and adapted to lie flat on said floor when opened, and serving to normally close a rectangular opening in said floor; of a hand rail, of inverted U-shape, hinged to said floor and adapted to be upturned in vertical position toward the front of said body;

70 75 80 85 90 95 100 105 110 115 120 125 130

braces upon opposite sides of said body arranged to serve as stop supports for said hand rail in its upturned position; means arranged to detachably secure said hand rail in its upright position, including hooks and eyes; a frame including a non-rotatable axle provided with two dirigible wheels at the front of said body; means pivotally securing said dirigible wheel frame to said body; a rigid tractor member pivotally connected to said frame and arranged to extend in front of said body and be upturned against said hand rail; whereby said dirigible wheels may be turned to steer the wagon; an axle frame, rigidly connected with said body, at the rear end thereof; an axle mounted to rotate in said rear axle frame and provided with one supporting wheel rigidly connected therewith upon one side of said body; another supporting wheel mounted to turn freely upon said rear axle at the opposite side of said body; a gear wheel rigidly connected with said rear axle; a treadmill mechanism, adapted to propel said wagon, including a gear wheel in mesh with said gear on said rear axle and rigidly connected with a rear driving shaft; journal bearings for said rear driving shaft, rigidly connected with said body at opposite sides of said opening; a front driving shaft, parallel with said rear driving shaft; journal bearings for said front driving shaft, rigidly connected with said body, at opposite sides of said opening, and arranged to support said front shaft at a higher level than said rear shaft; sprocket gear wheels respectively rigidly connected with said rear and front driving shafts, intermediate of the length thereof; an endless sprocket chain extending around said sprocket gears and operatively connecting said shafts; belt rollers on said shafts, extending upon axially opposite sides of said sprocket gears; an endless belt, formed of textile fabric, extending around said rollers, and having a longitudinal series of transverse slats arranged as footholds upon the outer face thereof; an idle roller, parallel with said front and rear shafts and extending between them and beneath the upper reach of said

endless belt, arranged to support the weight of the operator on said belt, within said opening; and journal bearings for said idle roller, at respectively opposite sides of said opening in said body; whereby, when said doors are opened and said hand rail and tractor raised, to cooperative relation, said wagon may be propelled by the weight of an operator bearing upon said belt and, when 5 said doors are closed and said hand rail and tractor lowered, said body affords a receptacle for the transportation of articles, and the wagon may be drawn by said tractor, regardless of said treadmill mechanism.

15 2. In a toy wagon, the combination with an express body, having a pair of trap doors in the floor thereof, and adapted to lie flat on said floor when opened, and serving to normally close an opening in said floor; of 20 a hand rail, hinged to said floor and adapted to be upturned in vertical position toward the front of said body; means arranged to detachably secure said hand rail in upright position; a frame provided with 25 two dirigible wheels at the front of said body; means pivotally securing said dirigible wheel frame to said body; a tractor member pivotally connected to said frame and arranged to extend in front of said body and be upturned against said hand rail; whereby said dirigible wheels may be turned to steer the wagon; an axle frame, connected with said body, at the rear end thereof; an axle mounted to rotate in said rear axle 30 frame and provided with a supporting wheel rigidly connected therewith upon one side of said body; another supporting wheel mounted to turn freely upon said rear axle at the opposite side of said body; a gear 35 wheel rigidly connected with said rear axle; a treadmill mechanism, adapted to propel said wagon, including a gear wheel in mesh with said gear on said rear axle and rigidly connected with a rear driving shaft; 40 journal bearings for said rear driving shaft, connected with said body at opposite sides of said opening; a front driving shaft, parallel with said rear driving shaft; journal bearings for said front driving shaft connected with said body, at opposite sides of said opening, and arranged to support said front shaft at a higher level than said rear shaft; sprocket gear wheels respectively connected with said rear and front driving 45 shafts, intermediate of the length thereof; an endless sprocket chain extending around said sprocket gears and operatively connecting said shafts; belt rollers on said shafts, extending upon axially opposite sides of said sprocket gears; an endless belt, extending around said rollers and having a longitudinal series of transverse slats arranged as footholds upon the outer face thereof; an idle roller parallel with said 50 front and rear shafts and extending between them and beneath the upper reach of said endless belt, arranged to support the weight of the operator on said belt, within said opening; whereby, when said doors are opened and said hand rail and tractor raised, to cooperative relation, said wagon may be propelled by the weight of an operator bearing upon said belt and, when said doors are 55

them and beneath the upper reach of said endless belt, arranged to support the weight of the operator on said belt, within said opening; and journal bearings for said idle roller, at respectively opposite sides of said opening in said body; whereby, when said doors are opened and said hand rail and tractor raised, to cooperative relation, said wagon may be propelled by the weight of an operator bearing upon said belt and, 70 when said doors are closed and said hand rail and tractor lowered, said body affords a receptacle for the transportation of articles and the wagon may be drawn by said tractor, regardless of said treadmill mechanism.

75 3. In a toy wagon, the combination with an express body, having a pair of trap doors in the floor thereof, serving to normally close an opening in said floor; of a 80 hand rail, adapted to be upturned in vertical position toward the front of said body; means arranged to detachably secure said hand rail in its upright position; a frame provided with two dirigible wheels at the 85 front of said body; means pivotally securing said dirigible wheel frame to said body; a rigid tractor member arranged to extend in front of said body and be upturned against said hand rail; whereby said dirigible wheels may be turned to steer the wagon; an axle frame, connected with said body, at the rear end thereof, an axle mounted to rotate in said rear axle frame and provided with one supporting wheel rigidly connected 90 therewith upon one side of said body; another supporting wheel mounted to turn freely upon said rear axle at the opposite side of said body; a gear wheel rigidly connected with said rear axle; a treadmill 95 mechanism, adapted to propel said wagon, including a gear wheel in mesh with said gear on said rear axle and rigidly connected with a rear driving shaft; a front driving shaft, parallel with said rear driving shaft, 100 at a higher level than said rear shaft; sprocket gear wheels respectively rigidly connected with said rear and front driving shafts; an endless sprocket chain extending around said sprocket gears and operatively 105 connecting said shafts; belt rollers on said shafts; an endless belt, extending around said rollers and having a longitudinal series of transverse members arranged as footholds upon the outer face thereof; an idle roller parallel with said front and rear shafts and extending between them and beneath the upper reach of said endless belt, arranged to support the weight of the operator on said belt, within said opening; whereby, when said doors are opened and said hand rail and tractor raised, to cooperative relation, said wagon may be propelled by the weight of an operator bearing upon said belt and, when said doors are 110

115

120

125

130

closed and said hand rail and tractor lowered, said body affords a receptacle for the transportation of articles and the wagon may be drawn by said tractor, regardless of 5 said treadmill mechanism.

4. In a toy wagon, the combination with an express body, having a trap door in the floor thereof, serving to normally close an opening in said floor; of a hand rail, adapted to be upturned toward the front of said body; means arranged to detachably secure said hand rail in its upright position; a frame provided with two dirigible wheels at the front of said body; means pivotally securing said dirigible wheel frame to said body; a rigid tractor member arranged to extend in front of said body and be upturned toward said hand rail; whereby said dirigible wheels may be turned to steer the 10 wagon; an axle frame, connected with said body, at the rear end thereof, an axle mounted to rotate in said rear axle frame and provided with a supporting wheel rigidly connected therewith upon one side of said body; another supporting wheel mounted to turn 15 freely upon said rear axle at the opposite side of said body; a gear wheel rigidly connected with said rear axle; a treadmill mechanism, adapted to propel said wagon, including a gear wheel in mesh with said gear on said rear axle and rigidly connected 20 with a rear driving shaft; a front driving shaft, parallel with said rear driving shaft, at a higher level than said rear shaft; sprocket gear wheels respectively rigidly connected with said rear and front driving shafts; an endless sprocket chain extending 25 around said sprocket gears and operatively connecting said shafts; belt rollers on said shafts; an endless belt, extending around said rollers and having a longitudinal series 30 of transverse members arranged as footholds upon the outer face thereof; and means arranged to support the weight of the operator on said belt, within said opening; whereby, when said door is opened and said hand rail and tractor raised, to cooperative 35 relation, said wagon may be propelled by the weight of an operator bearing upon said belt and, when said door is closed, said body affords a receptacle for the transportation 40 of articles and the wagon may be drawn by said tractor, regardless of said treadmill mechanism.

35 gear wheels respectively connected with said rear and front driving shafts; an endless sprocket chain extending around said sprocket gears and operatively connecting said shafts; belt rollers on said shafts; an endless belt, extending around said rollers and having a longitudinal series of trans- 45 verse members arranged as footholds upon the outer face thereof; and means arranged to support the weight of the operator on said belt, within said opening; whereby, when said door is opened, said wagon may be propelled by the weight of an operator bearing upon said belt and, when said door is closed, said body affords a receptacle for 50 the transportation of articles and the wagon may be drawn by said tractor, regardless of said treadmill mechanism.

5. In a toy wagon, the combination with a body, having a trap door in the floor thereof, serving to normally close an opening in said floor; of a frame provided with two dirigible wheels at the front of said body; means pivotally securing said dirigible wheel frame to said body; a rigid tractor member pivotally 55 connected to said frame and arranged to extend in front of said body and be upturned; whereby said dirigible wheels may be turned to steer the wagon; an axle frame, rigidly connected with said body, at the rear end thereof, an axle mounted to rotate in said rear axle frame and provided with a supporting wheel rigidly connected 60 therewith upon one side of said body; another supporting wheel mounted to turn freely upon said rear axle at the opposite side of said body; a gear wheel rigidly connected with said rear axle; a treadmill mechanism, adapted to propel said wagon, including a gear wheel in mesh with said gear on said rear axle and rigidly connected 65 with a rear driving shaft; a front driving shaft, parallel with said rear driving shaft, at a higher level than said rear shaft; sprocket gear wheels respectively rigidly connected with said rear and front driving shafts; an endless sprocket chain extending around said sprocket gears and operatively connecting said shafts; belt rollers on said shafts; an

in said rear axle frame and provided with one supporting wheel rigidly connected therewith upon one side of said body; another supporting wheel mounted to turn freely upon said rear axle at the opposite 70 side of said body; a gear wheel rigidly connected with said rear axle; a treadmill mechanism, adapted to propel said wagon, including a gear wheel in mesh with said gear on said rear axle and rigidly connected 75 with a rear driving shaft; a front driving shaft, parallel with said rear driving shaft, at a higher level than said rear shaft; sprocket gear wheels respectively rigidly connected with said rear and front driving 80 shafts; an endless sprocket chain extending around said sprocket gears and operatively connecting said shafts; belt rollers on said shafts; an endless belt, extending around said rollers and having a longitudinal series 85 of transverse members arranged as footholds upon the outer face thereof; and means arranged to support the weight of the operator on said belt, within said opening; whereby, when said door is opened and said hand rail and tractor raised, to cooperative 90 relation, said wagon may be propelled by the weight of an operator bearing upon said belt and, when said door is closed, said body affords a receptacle for the transportation 95 of articles and the wagon may be drawn by said tractor, regardless of said treadmill mechanism.

6. In a toy wagon, the combination with a body, having a door in the floor thereof, and serving to normally close an opening in said floor; of a frame provided with two dirigible wheels at the front of said body; means pivotally securing said dirigible wheel frame to said body; a rigid tractor member arranged to extend in front of said body and be upturned; whereby said dirigible wheels may be turned to steer the wagon; an axle frame, rigidly connected with said body, at the rear end thereof, an axle mounted to rotate in said rear axle frame and provided with a supporting wheel rigidly connected therewith upon one side of said body; another supporting wheel mounted to turn 100 freely upon said rear axle at the opposite side of said body; a gear wheel rigidly connected with said rear axle; a treadmill mechanism, adapted to propel said wagon, including a gear wheel in mesh with said gear on said rear axle and rigidly connected 105 with a rear driving shaft; a front driving shaft, parallel with said rear driving shaft, at a higher level than said rear shaft; sprocket gear wheels respectively rigidly connected with said rear and front driving shafts; an endless sprocket chain extending around said sprocket gears and operatively connecting said shafts; belt rollers on said shafts; an 110

115

120

125

130

endless belt, extending around said rollers and having a longitudinal series of transverse members arranged as footholds upon the outer face thereof; and an idle roller 5 parallel with said front and rear shafts and extending between them and beneath the upper reach of said endless belt, arranged to support the weight of the operator on said belt, within said opening; whereby, 10 when said door is opened, said wagon may be propelled by the weight of an operator bearing upon said belt and, when said door is closed, said body affords a receptacle for the transportation of articles and the wagon 15 may be drawn by said tractor, regardless of said treadmill mechanism.

7. In a toy wagon, the combination with a body, having a pair of trap doors in the floor thereof, hinged on axes parallel with 20 the length of said body and adapted to lie flat on said floor when opened, and serving to normally close a rectangular opening in said floor; of a hand rail, adapted to lie flat on said floor and be upturned in vertical 25 position; means arranged to detachably secure said hand rail in its upright position; a frame provided with two dirigible wheels at the front of said body; means pivotally securing said dirigible wheel frame to said 30 body; a rigid tractor member arranged to extend in front of said body and be upturned; whereby said dirigible wheels may be turned to steer the wagon; an axle frame, rigidly connected with said body, at the rear 35 end thereof, an axle mounted to rotate in said rear axle frame and provided with a supporting wheel rigidly connected therewith upon one side of said body; another

supporting wheel mounted to turn freely upon said rear axle at the opposite side of 40 said body; a gear wheel rigidly connected with said rear axle; a treadmill mechanism, adapted to propel said wagon, including a gear wheel in mesh with said gear on said rear axle and rigidly connected with a rear 45 driving shaft; a front driving shaft, parallel with said rear driving shaft, at a higher level than said rear shaft; sprocket gear 50 wheels respectively rigidly connected with said rear and front driving shafts; an endless sprocket chain extending around said sprocket gears and operatively connecting 55 said shafts; belt rollers on said shafts; an endless belt, extending around said rollers and having longitudinal series of transverse members arranged as footholds upon the outer face thereof; and means, arranged to support the weight of the operator on said belt, within said opening; whereby, when 60 said doors are opened and said hand rail and tractor raised, to cooperative relation, said wagon may be propelled by the weight of an operator bearing upon said belt and, when said doors are closed and said hand rail and tractor lowered, said body affords 65 a receptacle for the transportation of articles and the wagon may be drawn by said tractor, regardless of said treadmill mechanism.

In testimony whereof, I have hereunto signed my name at Philadelphia, Pennsylvania, this tenth day of October, 1924.

HARRY KISTER.
